UNITED STATES PATENT OFFICE.

MATHIAS WARNER, OF JONESBURG, MISSOURI.

END-GATE.

SPECIFICATION forming part of Letters Patent No. 656,915, dated August 28, 1900.

Application filed June 23, 1900. Serial No. 21,290. (No model.)

To all whom it may concern:

Be it known that I, MATHIAS WARNER, a citizen of the United States, residing at Jonesburg, in the county of Montgomery and State 5 of Missouri, have invented certain new and useful Improvements in End-Gates; and I do declare the following to be a full, clear, and exact description of the invention, such as will enable others skilled in the art to which 10 it appertains to make and use the same.

My invention relates to improvements in end-gates or closures for wagons, bins, and the like; and its object is to provide an end-gate fastening which avoids the use of rods 15 and similar fastenings and which is simple in construction and adapted to permit of the easy and quick application and removal of the end-gate.

With these and other minor objects in view 20 the invention consists in certain novel features of construction, combination, and arrangement of parts, as will be hereinafter more fully described, and particularly pointed out in the appended claim.

25 In the accompanying drawings, Figure 1 is an end view showing the application of my invention to a vehicle-body. Fig. 2 is a vertical cross-section through the vehicle-body and a longitudinal section through the end-gate. Fig. 3 is a horizontal section through 30 the parts shown in Fig. 2. Fig. 4 is a detail view of the bail.

Referring now more particularly to the drawings, in which like reference characters 35 designate corresponding parts throughout the several views, the numeral 1 represents the body of a wagon, bin, or other like container, which may be of the usual or any preferred construction, and 2 is the end-gate, arranged 40 to close the open end of the body in the usual manner. The side-boards 3 of the body are provided at their rear ends with wear-plates 4, which are of U form and embrace the sides and lower ends of the boards, but may consist 45 simply of plates applied to the inner sides or faces of said boards 3. To the wear-plate portions or sections upon the inner sides of the boards are applied vertical distance-strips 5, to which are centrally secured retaining-strips 6, which have their opposite side edges 7 free and spaced apart from the wear-plates to provide opposite longitudinal

grooves 8 for the reception of the locking devices on the end-gate. The free edges of the keeper strips or plates are thus adapted 55 to have a certain flexibility and freedom of movement and to exert a spring binding action on the locking devices of the end-gate, as hereinafter described.

The end-gate 2 is provided at each of its 60 ends with a pair of locking-plates 9, secured upon opposite sides thereof and projecting beyond the ends of the gate, the free projecting ends being bent laterally toward each other to form hooks or tongues 10, which are 65 adapted to slidably engage the free edges of the keeper strips or plates and to fit and slide within the grooves 8 thereof. These hooks or tongues are adapted, when the end-gate is applied to bear against the central distance- 70 pieces to which the keeper-strips are connected, to guide the end-gate in its movements and to also frictionally engage between the wear-plates and the projecting side edges of the keeper-strips to hold the end-gate 75 firmly in position and prevent it from working either up or down when the wagon-body oscillates or plays freely on its sustaining-springs as a result of the jarring or jolting 80 action of the running-gear.

In applying the end-gate it is held vertically above the body, and its locking-tongues are brought into coincidence with the grooves formed by the keeper-strips and are then forced down in said grooves to close the open 85 end of the body. To remove the end-gate, the reverse operation is carried out—that is, the end-gate is drawn upwardly until the tongues are entirely withdrawn from the grooves, when the gate may be removed. A 90 pivoted loop or bail 11 is applied to the end-gate and serves the combined purpose of a handle to facilitate the removal of the gate and a lock to hold the gate closed. The bail is pivoted at its ends in eyes 12, and one of 95 the ends is extended and bent at right angles to form a hook or catch 13, adapted, when the bail hangs down, to engage a pin 14 on the body to hold the gate locked. When the bail is swung up, the catch is withdrawn from engagement with the pin and the gate left free 100 to be lifted out. The frictional engagement between the tongues of the end-gate and the free side edges of the keeper-strips adapts

the gate to be elevated or opened to any desired extent and to be supported securely in its adjusted position.

From the foregoing description, taken in connection with the accompanying drawings, the construction and mode of operation of the invention will be readily understood.

By providing an end-gate fastening of this type the mounting of the gate is materially simplified, rods and other complicated attachments dispensed with, and the gate adapted to be entirely removed and applied with ease and facility.

Having thus described my invention, what I claim, and desire to secure by Letters Patent, is—

In an end-gate for vehicles, bins and the like, the combination, with the side-boards

thereof, of wear-plates upon the inner faces of said side-boards and carrying distance-pieces, retaining-plates secured centrally to said distance-pieces and having free side edges spaced apart from the wear-plates and forming in connection therewith longitudinal grooves, an end-gate, and locking-plates arranged in bearings at each end of the gate and provided with inwardly-projecting tongues to slide within said grooves, substantially as described.

In testimony whereof I have hereunto set my hand in presence of two subscribing witnesses.

MATHIAS WARNER.
